UNITED STATES PATENT OFFICE.

JOHN C. JOHNSON, OF PHILADELPHIA, PENNSYLVANIA.

DESIGN FOR A SYRUP-CAN.

SPECIFICATION forming part of Design No. 35,364, dated December 3, 1901.

Application filed October 21, 1901; Serial No. 79,488. Term of patent 7 years.

To all whom it may concern:

Be it known that I, JOHN C. JOHNSON, a citizen of the United States, residing at the city of Philadelphia, in the county of Philadelphia and State of Pennsylvania, have invented and produced a new and original Design for Syrup-Cans, of which the following is a specification, reference being had to the accompanying drawings, forming part hereof, in which—
o Figure 1 is a front elevational view of a syrup-can, showing my design. Fig. 2 is a side elevational view of the same, and Fig. 3 is a top or plan view of the can.

As illustrated in the drawings, the leading or material feature of my design consists of the configuration of the front and body of the can. As viewed in front elevation the can presents the appearance of two superposed cylinders, of which the upper, *a*, is of larger diameter than the lower cylinder *b*. As

viewed in side elevation and in plan the body *d* of the can is substantially rectangular and has at its front a semicylindrical projection. Depending from the base of the body *d*, adjacent to the semicylindrical front, is a cylindrical projection capped or surmounted by a ring or rings *b'* of larger diameter than the cylinder *b*, as shown in Fig. 2.

Having thus described my invention, what I claim as new, and desire to secure by Letters Patent, is—

The design for a syrup-can, substantially as herein shown and described.

In testimony whereof I have hereunto set my signature in the presence of two subscribing witnesses.

JOHN C. JOHNSON.

Witnesses:

J. WALTER DOUGLASS,
THOMAS M. SMITH.
